MACHINES FOR PROCESSING LEATHER

Ernst Schödel, Dusseldorf, Germany, assignor to Rheinmetall Aktiengesellschaft, Dusseldorf, Germany

Application June 25, 1954, Serial No. 439,379

Claims priority, application Germany July 2, 1953

8 Claims. (Cl. 69—34)

The present invention relates to a universal staking and finishing machine for the processing, and more especially the softening, of leather or pelts, having a rotating knife cylinder; a resilient pressure device for the work-piece adapted to be moved against the knife cylinder, and a workpiece holding device or starting frame adjustable in a vertical direction.

In machines of this type the processing of the leather, that is to say the staking, sleeking and buffing, is performed by the knife cylinder rotating at considerable speed and having the individual knives (staking blades) arranged in oppositely directed spirals from the centre of the cylinder towards each end thereof. The leather or pelt to be processed is clamped with one edge in the workpiece holder or staking frame, and is pressed by means of the resilient pressure device, such as, for example, a leather pad, with its flesh side against the cylinder so that the blades, inclined to the left and to the right respectively, stake the leather sideways. Since, at the same time, the staking frame is reciprocated in the vertical direction all portions of the workpiece come successively within the reach of the knife cylinder. As a result, the leather is intensively subjected to thorough working up in all directions.

It is an object of the invention to provide a machine of the type referred to which can be operated with a minimum of energy and which enables the material to be worked up very gently. More especially it is directed to enabling the operating components, that is to say the staking frame and the pressure device, to be controlled by "touch." Thus, for example, a slight pressure on the control lever of the pressure device should cause the workpiece to be pressed gently, and stronger pressure should cause it to be pressed hard against the knife cylinder. In a similar manner a slight pressure on the control lever of the staking frame drive should cause the frame to rise slowly and a strong pressure should cause the frame to rise rapidly. The invention further aims at providing a compact arrangement and simple installation of the machine, smooth operation of the drives for the staking frame and the pressure device, and ready adaptability of the machine to the different qualities of leathers and/or pelts to be processed.

According to the invention the pressure device and the workpiece holder are operated hydraulically through suitably designed working cylinders, each cylinder being connected with a pressure fluid circulating system separately connected to a fluid containing tank and adapted to be individually adjusted by means of a throttling means.

This special arrangement of the hydraulic system results, in the first place, in the machine operation being simple and requiring almost no exertion at all on the part of the operator and the possibility of handling the controls by "touch." Since the pressure fluid circulating system for the working cylinder of the staking frame is completely independent of the system operating the working cylinder of the pressure device, each cylinder can be op-

2

erated under the most advantageous hydraulic conditions so that the designer has a completely free hand in designing these elements whereby particularly economical construction and working is ensured.

5 The invention will be described in more detail with reference to one embodiment thereof shown in the drawings in which—

Fig. 1 is an elevation, showing in diagrammatic form the essential components of a universal staking machine

10 according to the invention,

Fig. 2 is a plan view of the staking frame and the knife cylinder, likewise shown diagrammatically,

Fig. 3 is an elevation, partly in section, of a valve box with control valve, control lever and associated operating links,

Fig. 4 is a longitudinal section of a control valve,

Fig. 5 shows in longitudinal section the working cylinder for the operation of the staking frame, with the components retracted (staking frame in the lower position), and

Fig. 6 is a longitudinal section through the working cylinder for the pressure device, with the components likewise fully retracted, that is to say with the pressure device removed from the knife cylinder.

25 The machine as shown in the drawings comprises an upright frame 1 on either side of which the knife cylinder 2 is rotatably supported in pedestals (not shown in drawing). The knife cylinder (Fig. 2) is made up of a basic body of, for example, hexagonal cross-section, provided with staking knives 3, 4 arranged in two sets starting from the centre of the cylinder in a lefthand and a righthand spiral respectively. The knife cylinder 2 is rotated by an electric motor (not shown in drawing) through multiple V-belts or the like.

35 The pressure device which presses the workpiece to be processed against the knife cylinder comprises a pad in the form of an endless leather belt 5 slung about a frame-like carrier 6. Compression springs 7, the tension of which can be adjusted by means of threaded nuts 8, 40 maintain an even, predetermined tension of the leather belt 5. Rigidly connected with the carrier frame 6 there is a shaft 9 which in turn is rotatably supported in bearings (not shown in drawing) attached to the machine frame 1. This shaft 9 is further rigidly connected with a lever 10 on the free end of which the plunger 12 of the hydraulically operated cylinder (see also Fig. 6) acts through a ball-and-socket joint 11, 11a, the cylinder body of said working cylinder being indicated at 13 and

45 Fig. 1. The bottom end of the cylinder body is connected through a ball 14 and socket 15 with a fixed part 16 of the machine frame. When the plunger 12 is moved outwardly from the cylinder in a manner to be described below, the lever 10, together with the frame 6 and the pressure pad 5, swivels correspondingly about the shaft 50 9 so that the pad 5, and with it the workpiece, is pressed against the knife cylinder 2.

55 The workpiece carrier, or staking frame comprises a frame-like structure 17 at the front edge of which there is provided a clamping device (not shown in drawing) 60 for the workpiece which clamping device can be operated by means of a handle 18 (Fig. 2). In rigid connection with the frame 17 there are guide members 19 and 20 which permit vertical reciprocation of the frame while at the same time positively preventing any tilting of the frame. These guide members 19, 20 are guided in sliding bushes 21, 22 attached to a fixed frame 23 positioned for example on the axis of symmetry of the machine. Instead of the two guides 19, 20 shown in the drawings, there may be provided with advantage three such guides

65 70 for the staking frame so that, in addition to the guide members 19 there are two guide members 20. The arrangement then forms a three-point suspension system

for the staking frame and thereby ensures a particularly positively guided frame.

The operation that is to say the vertical reciprocation, of the staking frame 17 is effected by means of a hydraulic cylinder (see, more especially, Fig. 5) which is located inside the guide member 19. The said cylinder comprises an external tubular sleeve 24 and an internal plunger rod 25. The sleeve 24 and plunger rod 25 are respectively rotatably and pivotally connected through ball-and-socket joints 26 and 27 with the guide member 19, and thereby with the staking frame and the machine frame respectively; in this manner ensuring that any inaccuracy in the manufacture or assembly of the component parts of the machine have no disadvantageous effect on the effective operation of the machine. In addition, the provision of the said ball-and-socket joints enables a certain degree of inaccuracy, due to normal wear and tear, to be positively compensated.

The hydraulic system operating the working cylinders described above consists of two pressure pumps located in a common housing 28 but functioning independently, the common drive of which is provided by an electric motor 29. The suction sides of both pumps are joined to a common suction pipe 30 connected with a pressure liquid tank 31. The pressure sides of the two pumps, on the other hand, are separately connected as will be hereinafter described.

In operating the staking frame 17 the pressure liquid performs the following cycle:

The pressure liquid for example oil, delivered from the pressure side 32 of the relevant pump flows normally through a control valve 33 in its open or non-operated position, through pipes 34 and 35 and is cycled back into the tank 31. The liquid pressure thereby generated in a branch pipe 36 leading to the working cylinder 24 is insufficient to overcome the weight of the staking frame. As a result the frame remains in the rest position while the pump unit is working.

When the valve 33 is partially closed by depressing a hand control lever 37, the restricted flow of the pressure liquid increases the pressure inside the pipes 34 and 36. According to the speed at which the valve 33 is closed, the cylinder 24 of the staking frame cylinder moves upwardly at a corresponding speed. During this movement, the pressure oil flows (see, more especially, Fig. 5) from the pipe 36 via a bore 38 into a longitudinal bore 39 of the plunger rod 25. To ensure a smooth start a special damping device is provided inside the bore 39 and comprises an auxiliary plunger 40 which, in the bottom stationary position of the working cylinder, covers slots 41 of the plunger rod 25 with its cylindrical surface and with a tappet-like extension 42 rests against the end 43 of the cylinder. The auxiliary plunger is constantly acted upon by a pressure spring 44, and the stroke of the plunger in the outward direction is limited by a stop ring 45.

The damping device described above functions in the following manner:

When the control lever 37 of the staking frame operating valve 33 is depressed, that is to say when the valve 33 is partially closed, the elements of the working cylinder are in the positions shown in Fig. 5. The pressure liquid flowing to the longitudinal bore 39 can thus reach the cylinder chamber 47 only through a comparatively very small bore 46 in the plunger 40. The sleeve 24 will consequently at first very gradually move upwards. In this movement it is accompanied by the auxiliary plunger 40 under the pressure exerted upon it by the spring 44 until the top edge of said auxiliary plunger comes to rest against the ring 45. In the meantime, however, the auxiliary plunger 40 has already increasingly opened the slots 41 forming main channel for the liquid so that the channel for the pressure liquid which had a very small cross-section initially, is progressively increased during the first phase of the plunger movement until

finally the working cylinder is under full pressure; this is roughly the case when the auxiliary plunger 40 registers against the ring 45.

To achieve appropriate damping also in the top dead centre position of the working cylinder 24, the latter is connected with a control sleeve 9' which, at the same time, also serves as a bearing guide for the plunger rod 25. As soon as the cylinder member 24 approaches the top position, this sleeve 9' covers the slots 41 externally to an increasing extent so that towards the end of the plunger movement the pressure liquid can flow only through the small bore 46, that is to say slowly.

On the return movement of the cylinder 24, and before the bottom position is reached, the damping device becomes likewise operative as a result of which the staking frame settles gently, under its own weight, on the rest provided for it on the machine frame.

Very similar conditions obtain in connection with the hydraulic system operating the working cylinder 12, 13, which, as explained above, actuates the pressure device. This working cylinder is shown in Fig. 1 in an intermediate position and in Fig. 6 in the unoperative position. It comprises a plunger 12 and a cylinder 13 provided with a guide bush 13'. When the control valve 48 is open, that is to say when the control lever 54 is not depressed, the pressure oil coming from the pressure side 49 of the second pump unit circulates through pipe 50, connection 50', the ring channel 51 (Fig. 6), the connection 52' and the pipe 52, the open valve 48 and the pipe 53 back to the tank 31. When the control lever 54 is depressed closing the valve 48, the resulting increased pressure forces the oil at first from the channel 51 through a small bore 54 to the underside of the plunger 12 which latter is thereby caused to start to move smoothly, outwardly of the cylinder 13 at a suitably slow rate. As soon as the edge 55 of the plunger has uncovered the inlet for the pressure liquid, the plunger is placed gradually under full pressure so that it moves outwards at speed, as and when required. A damping in the top position of the plunger is in this case generally not required because the resilient leather pad 5, which rests, together with the workpiece under suitable pressure against the knife cylinder, itself provides sufficient damping. In order to enable the maximum degree of contact pressure—which, as is known, varies with the type of leather or pelt to be worked—to be adjusted, it is advantageous to limit the top end of the stroke of the plunger 12 by a vertically adjustable stop 56. For this purpose the stop 56 can be provided with longitudinal slots 57, for fixing it in the adjusted position by means of screws 58.

In this case, too, the braking of the descending plunger 12 is effected by means of the damping device described above which leaves only a comparatively small cross-section open for the pressure oil to pass through. The plunger 12 returns to its inoperative position by the counterweight 10' and also by its own weight and the weight of lever 10.

As has been mentioned above, the working cylinders operating the staking frame and the pressure device are controlled through identical control valves by means of the control levers 37 and 54 respectively; as shown in Fig. 3, each of these levers is pivotally supported on the front wall of the machine frame by means of a pin 59. The power is transmitted to the control valves—designated as complete units by 33 and 48 respectively—by a rod 60 which is slidably in stationary guides 61, 62. To balance the weight of this linkage system and to compensate for the friction generated by the guides, there is provided a pressure spring 63 the initial tension of which can be adjusted by means of a threaded nut 64. The length of the stroke of the linkage system can be adjusted in either direction by means of milled nuts 65, 66.

With each linkage system 60 there is associated a control valve the details of which can be seen in Fig. 4. Essentially, such a valve consists of a housing 67 having

suitable unions 69, 68 for connecting to the pipes supplying and entraining the pressure liquid respectively. Inside the valve there is a valve member 70, provided with a suitable sealing means, the head of the member being slidably received in a pressure sleeve 71. The sleeve 71, in its turn, is slidable in a bore of the housing 67. The sleeve 71 effects sliding movement under the action of a compression spring 72 and, when the control lever 33 or 48 respectively is not depressed, the sleeve 71 rests with a shoulder formed in its surface engaging against a securing ring 73. Between a shoulder 74 on the valve member 70 and the underside of the pressure sleeve 71 a compression spring 75 is positioned. The unoperated position of the valve member 70, as well as the moment when an excess-pressure preventing device hereinafter described is released, are adjusted by means of threaded nuts 76.

The operation of the control valve is as follows:

In the normal unoperated position of the control lever 37, or 54 respectively (Fig. 3), the elements of the control valve are positioned as shown in Fig. 4, the valve member 70 not interrupting the channel 77 so that pressure liquid can circulate freely, the linkage 60 being so adjusted by means of the spring 63 that there is a certain, small amount of play between the lower end portion 78 (Fig. 3) of the rod 60 and the top end portion of the pressure sleeve 71. The adjusting nuts 76 of the control valve, together with the associated screw threaded top end of the valve member 70 are positioned within a bore 79 of the linkage 60, the diameter of said bore being large enough to allow sufficient freedom of movement for the nuts and the threaded end of the valve member 70.

When the control lever 37 or 54 respectively is depressed the movement of the linkage 60 is transmitted through the pressure sleeve 71 and the compression spring 75 to the valve member 70 which is thereby caused to move downwards and partially to restrict the cross-section of the channel 77.

When the control lever 33 is released upwardly the valve member 70 is returned to its normal position by the pressure of the liquid acting on the lower end thereof and, more especially, by the return spring 72.

In the arrangement described above the spring 75 also prevents excess-pressure because—with the pump connected and the control lever kept down permanently—the pressure of the liquid becomes so great that it can overcome the pressure of the spring 75 and in so doing it pushes the valve member 70 upwards relative to the pressure sleeve 71, the adjusting nuts 76 and the associated threaded end of the valve member 70 entering in the bore 79 of the linkage 60.

What I claim is:

1. A universal staking machine having a rotating knife cylinder, a resilient pressure device for the workpiece capable of being pressed against the knife cylinder, and a workpiece holder or staking frame capable of vertical reciprocation, means for operating the pressure device and the workpiece holder hydraulically including individual cylinders, a separate pressure liquid circulating system for each of said cylinders and throttle valve means controlling each system.

5 2. A universal staking machine having a rotating knife cylinder, a resilient pressure device for the workpiece capable of being pressed against the knife cylinder, and a workpiece holder or staking frame capable of vertical reciprocation, means for operating the pressure device and the workpiece holder hydraulically including individual cylinders, a separate pressure liquid circulating system for each of said cylinders and throttle valve means controlling each system, the staking frame being actuated by a single working cylinder located on the axis of symmetry of the said frame which is secured against tilting by guide members.

10 3. A universal staking machine having a rotating knife cylinder, a resilient pressure device for the workpiece capable of being pressed against the knife cylinder, and a workpiece holder or staking frame capable of vertical reciprocation, means for operating the pressure device and the workpiece holder hydraulically including individual cylinders, a separate pressure liquid circulating system for each of said cylinders and throttle valve means controlling each system, the staking frame being guided in stationary bearing bushes serving as sliding guides for guide rods attached to the staking frame, as well as for a tubular sleeve surrounding the operating cylinder of the staking frame.

25 4. A staking machine as claimed in claim 1, wherein the valve member of a control valve controlling operation of a cylinder is connected with a control lever, a compression spring being interposed between the valve member and the lever and serves as a device preventing excess-pressure, and the length of the stroke of the control lever being adjustable by means of stops.

30 5. A universal staking machine as claimed in claim 1, wherein a slideable and lockable stop is provided for regulating the top position of the operating cylinder for the pressure device.

35 6. A universal staking machine according to claim 1, wherein a damping device is provided for the operating cylinder of the staking frame comprises an auxiliary plunger slidably guided within a hollow plunger rod, and 40 acted upon by a spring and cooperating with channel openings of the plunger rod, the said auxiliary plunger being guided close to the bottom position of the cylinder by means of a tappet from the end of the cylinder and so designed as to open a small channel opening located in the auxiliary plunger itself for the pressure liquid to pass through, while at the same time partially covering channel openings in the plunger rod.

45 7. A staking machine as claimed in claim 1, wherein the operating cylinders are connected at either end by means of ball-and-socket joints to the machine frame and to the member to be actuated respectively.

50 8. A staking machine as claimed in claim 1, wherein the valve member of a control valve controlling operation of a cylinder is connected with a control lever, a compression spring being interposed between the valve member and the lever and serves as a device preventing excess-pressure.
